UNITED STATES PATENT OFFICE.

WILLIAM A. KNIPE, OF HAVERHILL, MASSACHUSETTS.

BOX-TOE PIECE FOR SHOES.

1,127,641.

Specification of Letters Patent.

Patented Feb. 9, 1915.

Application filed July 20, 1914. Serial No. 851,839.

To all whom it may concern:

Be it known that I, WILLIAM A. KNIPE, a citizen of the United States, residing at Haverhill, in the county of Essex and State of Massachusetts, have invented an Improvement in Box-Toe Pieces for Shoes, of which the following is a specification.

In the manufacture of shoes, it is common practice to terminate the leather portion of the vamp slightly beyond the rear edge of the tip, and complete the vamp with a textile portion which is connected thereto by a butt-joint, these textile end portions being known in the trade as "butters".

For the purpose of stiffening the toe, or making a "box" in the toe, this end portion, or "butter" has been treated with various self-hardening substances, one method of treatment being to saturate the material with a wax-like composition, which is liquid or freely flexible when heated, and stiff or substantially inflexible, when cold, and another to use a gum which hardens on the evaporation of a softener with which it is treated. In employing a vamp having a textile tip portion thus treated, certain difficulties have been encountered in the shoe manufacturing process. The material with which the tip portion is impregnated is usually of a more or less slippery nature, particularly when softened sufficiently to permit it to conform to the last, so that, in the process of lasting the shoe, it is difficult to secure a firm hold thereon, as the lasting pincers which engage the edge portion thereof, are liable to slip from the same. That is, it has been found practically impossible to secure a sufficiently firm hold on the saturated cloth, while softened, to enable the vamp to be drawn as tightly over the last as is desirable or necessary. Furthermore, the vamp and tip must always be cut large to provide material which may be grasped by the lasting pincers, and this excess material, particularly at the toe, must be removed after the shoe is lasted. One effective method of cutting away this material is to employ a trimming-wheel having a large number of small projecting teeth. In performing this latter operation on the saturated cloth, above referred to, the teeth of the wheel becomes filled with the wax-like substance, so that the wheel is prevented from operating satisfactorily. It is, moreover, very difficult to free the wheel from this material after its interstices have become filled therewith.

The object of my invention is to provide a form of vamp end-portion which is so provided with a stiffening composition, of the nature above referred to, that it will act as a box for the toe, and will not interfere with the operation of the lasting pincers, or with the effective operation of the trimming-wheel. I accomplish this object by providing a vamp end-portion of textile or felted material having the main inner portion thereof saturated with a stiffening material, and providing an unsaturated edge adapted to be engaged by the lasting pincers which is adapted to be, and is practically all trimmed off.

For a more complete understanding of my invention, reference is made to the accompanying drawing, in which:

Figure 1 is a plan view of a vamp end portion, or "butter" embodying my invention. Fig. 2 is an edge view thereof. Fig. 3 is a bottom plan view of a lasted shoe having a vamp embodying my invention. Fig. 4 is a sectional view on the line 4-4 of Fig. 3. Fig. 5 is a view similar to Fig. 3 showing the shoe ready for the application of the sole.

In the drawing *a* indicates a vamp end portion or butter which is adapted to be attached by a butt-joint to the leather vamp *b*, and is located beneath the tip *c*.

According to my invention the main inner portion of the end piece *a*, to its line of attachment to the sole, is saturated with a substance *d*, of the nature of paraffin or other wax-like or gum-like composition, which becomes liquid, semi-liquid or soft when heated or treated with a softener or becomes stiff and hard when cold or upon evaporation of the softener, leaving an unsaturated edge, or margin portion *e* about the sides and tip end, which projects beyond said line of attachment. The process of thus treating the end piece *a* may be performed in various ways as by providing a pad which corresponds in size to the portion which is to be saturated, then dipping the same in the substance while heated to liquid form, or softened by a softener, and then placing the pad on the portion to be saturated, so that this portion only absorbs the stiffening substance. The shoe is made in the ordinary manner, the stiffening substance being heated or softened before the shoe is lasted and, when it is lasted, the unsaturated edge-portion *e* may be firmly grasped by the last-

ing pincers, and the vamp may be pulled into place on the last without having the pincers engage the saturated portion of the vamp end piece, so that the saturating substance will not interfere with the lasting operation. After the shoe has been lasted, this unsaturated vamp edge portion *e*, as well as the corresponding edge portion of the tip *e*, is removed, and may be removed by the trimming-wheel above referred to, without having the operation thereof interfered with, or its teeth becoming filled, or clogged with said stiffening substance. As the vamp portion which remains is thoroughly saturated, the practical effect is the same as if the whole end piece had been previously saturated.

I claim:—

A box toe piece for shoes composed of a single sheet of textile material having a self-hardening, stiffening substance saturating the portion thereof within its line of attachment to the shoe sole, and having a constantly flexible, unsaturated edge-portion extending beyond said line of attachment, to provide tool-engaging means. 20 25

In testimony whereof, I have signed my name to this specification, in the presence of two subscribing witnesses.

WILLIAM A. KNIPE.
